UNITED STATES PATENT OFFICE

2,648,112

BUCKLE

Anna Neumann, Brooklyn, N. Y.

Application May 3, 1950, Serial No. 159,708

2 Claims. (Cl. 24—168)

1

The present invention relates to buckles and particularly to a fastener for adjusting belts, straps, or the like.

Fasteners of similar basic construction have been disclosed in my prior Patents No. 2,475,634, dated July 12, 1949, and No. 2,480,874, dated September 6, 1949. The fasteners of both said patents comprise a lower and an upper member, the latter being threaded through the former, to rest thereon in operative position. This arrangement required an opening in the lower member and particularly in buckles of smaller sizes, as for instance in shoe buckles it was somewhat difficult to thread the upper member through the lower member.

It is, therefore, one of the objects of the present invention to provide a fastener for adjusting belts, straps, or the like, which permits of easy threading of one into the other member independently of the size of the fastener.

It is another object of the present invention to provide a fastener for adjusting belts, straps, or the like, one member of which comprises two parts which are hinged together.

It is still another object of the present invention to provide a fastener for adjusting belts, straps, or the like, one member of which rests on the other member, while the belt, strap, or the like of the upper member is threaded sidewaysly into the lower member.

With these and other objects in view, which will become apparent in the following detailed description, the present invention will be clearly understood in connection with the accompanying drawing, in which

Fig. 1 is an exploded top plan view of the fastener;

Fig. 2 is a top plan view of the fastener shown in Fig. 1, the upper member resting on the lower member in operative position;

Fig. 3 is a section along the line 3—3 of Fig. 2;

Fig. 4 is an exploded top plan view of the fastener shown in Fig. 1, however, the lower member having two hinged parts;

Fig. 5 is a top plan view of the fastener shown in Fig. 4, the upper member resting on the lower member in operative position;

Fig. 6 is a section along the lines 6—6 of Fig. 5;

Fig. 7 is an exploded top plan view of a fastener, the lower member of which has two oppositely disposed openings;

Fig. 8 is a top plan view of the fastener shown in Fig. 7 in operative position;

Fig. 9 is a section along the lines 9—9 of Fig. 8;

Fig. 10 is an exploded top plan view of a fastener similar to that of Fig. 1;

Fig. 11 is a top plan view of the fastener shown in Fig. 10 in operative position;

5 Fig. 12 is a section along the lines 12—12 of Fig. 11;

Fig. 13 is an exploded top plan view of the fastener having two openings disposed on the same side of the lower member;

10 Fig. 14 is a top plan view of the fastener shown in Fig. 13 in operative position;

Fig. 15 is a section along the lines 15—15 of Fig. 14;

15 Fig. 16 is a top plan view of another embodiment of a fastener having two openings disposed on the same side of the lower member;

Fig. 17 is a section along the lines 17—17 of Fig. 16; and

Fig. 18 is an end view of the fastener shown 20 in Fig. 16.

Referring now to the drawing and particularly to Figs. 1 to 3, the fastener comprises a frame-like lower member 1 and an upper member 2 which rests on the lower member 1 and 25 overlaps preferably, at least the ends thereof in operative position. Strap portions of the respective ends of a belt or the like 3 and 4 are immovably associated with the respective members 1 and 2. In the embodiment shown in Figs. 1 to 3 the lower member comprises a preferably

30 rectangular frame 5 which has one side opening 6 adjacent to one end of the frame 5 which opening communicates with a slot and serves the purpose to receive the belt 4 threaded through the upper member 2. As stated the belt 3 is immovably associated with the frame 5 and for this purpose three cross bars 7, 8 and 9, are provided intermediate to the ends of the frame 5. As particularly shown in Fig. 3, the belt 3 is threaded from below between one end of the frame 5 and the first cross bar 7 then passing in the same direction above the cross bars 8 and 9 and then below the cross bars 8 and 9 in opposite direction and further above the first cross bar 7.

35 40 45 The upper member 2 has, preferably, two crosswise extending longitudinally spaced slots 10 which receive the belt 4 in such manner that it passes from below through the first of said slots 10, then on top of the member 2 and finally through the other slot 10 below the member 2.

In order to put the two members 1 and 2 into operative position, the portion of the belt 4 which is remote from its end is threaded through 50 55 the side opening 6 of the frame 5, the member

2 then put on top of the member 1 and finally the end of the belt 4 threaded through the frame 5 between its end and the first cross bar 7, thereby maintaining the upper member 2 resting on the lower member 1 in operative position. The upper member 2 may be of any shape or size, and is not limited in its size to the width of the lower member 1, since no threading of the upper member 2 through the lower member 1 takes place.

In the embodiment shown in Figs. 4 to 6 the same principle as shown in the prior embodiment is applied and the only distinction lies in the lower member 1¹ which comprises two ring-shaped elements 5¹ and 5a¹, the element 5¹ having a side opening 6¹ to receive the belt 4¹, and both elements being hingedly connected. The belt 3¹ is immovably associated with the ring element 5a¹ and the upper member 2¹ extends, preferably, over the entire length and beyond the lower member 1¹. As shown in Fig. 6 a separate squarely shaped element 5b¹ may be hinged to the element 5a¹.

The embodiment shown in Figs. 10 to 12 is merely distinguished over the first two embodiments by the particular shape of the lower member 1², which is also equipped with one side opening 6² and thus operates in the same manner.

While the first three disclosed embodiments permit of threading of the remote end of the belt 4 of the upper member 2 through the side opening, the immediate end of the belt still has to be threaded through the lower member 1. The following embodiments, to be disclosed now, eliminate any threading through the lower member.

This end is achieved by providing side openings at both ends of the lower member. In the embodiment shown in Figs. 7 to 9, the lower member 1³ has a side opening 6a³ at one end thereof and another side opening 6b³ adjacent to the other end of the lower member 1³ and oppositely disposed to the opening 6a³. The upper member 2³ has immovably associated thereto the belt or strap 3³, while the belt or strap 4³ is secured, as by threading, through the upper member 2³.

Figs. 13 to 15 disclose substantially the same arrangement as shown in Figs. 7 to 9, however, the side openings 6a⁴ and 6b⁴ of the lower member 1⁴ are disposed on the same side thereof. The belts or straps 3⁴ and 4⁴ are immovably associated to the respective members 1⁴ and 2⁴ and the immediate and remote ends of the belt 4⁴ are inserted through the side openings of the member 1⁴ in order to reach the operative positions of the members 1⁴ and 2⁴. The upper member 2⁴ is shown in this embodiment in ribbon form though any other form may be used.

The embodiment shown, finally, in Figs. 16 to 18, shows a lower member 1⁵ which is equipped with two parallel longitudinally displaced open slots 6a⁵ and 6b⁵, which slots are inwardly curved at their open ends. In addition, as shown particularly in Fig. 17, the end portions of the lower member 1⁵ are lowered relative to the main body of said member. One of said end portions has its extreme end bent upwardly, as clearly shown in Fig. 18, to prevent that the belt 4⁵ be removed involuntarily or accidentally from the slots 6b⁵. The belt or strap 3⁵ is immovably associated to the lower member 1⁵.

While I have disclosed several embodiments of the present invention, it is to be understood that these embodiments are given by example only and not in any limiting sense, the scope of the invention being determined by the objects and the claims.

I claim:

1. In a fastener for adjusting belts, straps or the like, a lower member and an upper member, two slots in the said lower member, the greatest dimension of the said slots in the lower member being smaller than the smallest outer dimension of the said upper member, at least one cross-wise disposed opening in the said lower member and terminating in one of the said slots, the upper member resting on and at least partly overlapping both ends of the said lower member in operative position, one strap portion immovably associated with the said lower member in normal use of the fastener, another strap portion passing always in the same direction along the lower member and through one of the slots of the latter, then passing through and along at least a part of the upper member and finally again through the other of said slots of the said lower member, said other strap portion being immovably associated with the upper member during normal use of the fastener.

2. In a fastener for adjusting belts, straps or the like, a lower member and an upper member, two slots in the said lower member, the greatest dimension of the said slots in the lower member being smaller than the smallest outer dimension of the said upper member, at least one cross-wise disposed opening in the said lower member and terminating in one of the said slots, at least two parallel substantially crosswise disposed slots in the said upper member, the said upper member resting on and at least partly overlapping both ends of the lower member in operative position, one strap portion immovably associated with the said lower member in normal use of the fastener, another strap portion passing always in the same direction along the lower member and through one of the said slots of the latter, then being threaded through the said crosswise disposed slots of the upper member and passing along at least a part of the latter and finally again through the other of the said slots of the said lower member, said other strap portion being immovably associated with the upper member by means of the said threading through the upper member during normal use of the fastener.

ANNA NEUMANN.
